Inventor:
Arthur Ouellet
by J. W. Harris
Attorney.

UNITED STATES PATENT OFFICE.

ARTHUR OUELLET, OF NASHUA, NEW HAMPSHIRE.

CORD-GRIPPING DEVICE.

Application filed August 18, 1924. Serial No. 732,592.

To all whom it may concern:

Be it known that I, ARTHUR OUELLET, a subject of the King of Great Britain, and native of the Province of Quebec, Canada, and resident of Nashua, in the county of Hillsborough and State of New Hampshire, have invented certain new and useful Improvements in Cord-Gripping Devices, of which the following is a specification.

10 This invention relates to means for suspending articles such as plumb bobs and electric lamps in desired locations without requiring the tying of any knots in the suspending cord.

15 When a house is being built, it is customary for the mason or carpenter to hang a plumb bob from an overhead line, and when the weight is to be shifted in vertical position, and sometimes when to be shifted along

20 the overhead line, the existing knots must be un-tied and then new knots made. This involves a loss of time which is saved by my improved device. Moreover the tying of the knots requires expert work to effect suspension of the plumb bob in exactly the correct position. With my device the exact position can be easily and quickly secured and maintained.

Many machine shops require, at times, 30 that an electric lamp shall be located, perhaps temporarily, in a convenient illuminating place relatively to a particular machine, and it is customary to then use a string tied at one end to the circuit-wire cord and then 35 so manipulate the string and tie it that the lamp will hang in the desired position. As will be readily understood from the following description and the accompanying drawings, my suspension device will enable an 40 electric lamp to be quickly suspended in the position needed.

Of the drawings:—

Figure 1 illustrates my invention in use in connection with a plumb bob.

45 Figure 2 is a side elevation of the N-shaped hook.

Figure 3 is an edge view of the same.

Figure 4 is a side elevation of the upper part of the reel or carrier for surplus cord.

50 Figure 5 is an edge view of the same.

Similar reference characters indicate similar parts in all of the views.

The principal element of my device consists of a thin metal N-shaped hook or clip

55 A the two cord-biting notches α of which are

substantially parallel but opening in opposite directions. The walls of the notches are straight except at their extreme inner and outer ends, and each notch is very slightly tapering in form so that a cord such as illustrated at D in Figure 1 will be reliably permanently pinched when drawn toward the inner end of such notch.

A plumb bob, such as used by masons or carpenters, is illustrated at B, the cord for suspending it being indicated at D. C indicates the usual overhead line from which the plumb bob or other weight or device is to hang, and E indicates the reel or carrier which I provide for surplus cord D. One arm of the reel or carrier E is provided with a thin metal extension A' having a notch α' of the same character as either of the notches α in the N-shaped hook or clip A.

When the invention is to be utilized as illustrated by Figure 1, it is preferable to employ two of the compound hooks A, the upper one being engaged by or with the overhead line C and with the suspending cord D, while the lower one is engaged with the suspending cord D at two points so as to maintain a loop in the latter. Such use enables the height at which the plumb bob or other weight shall hang to be adjusted without touching, or having to reach up to, the upper hook A, because all variation in the vertical position of the weight can be effected by varying the amount of cord contained in the loop hanging from the lower hook A. The upper hook can usually be left undisturbed so long as its position along the line C needs no adjustment. When the weight needs to be raised or lowered, either notch of the lower hook can be caused to grip the cord D at a new point.

Owing to the fact that the two gripping notches α , α' , are substantially straight and parallel, and open in opposite directions, the compound hook when hung on one line, as the line C, will not tip far over and will therefore present its other notch in upwardly open position ready to receive the other cord, as D, without requiring hand manipulation of the hook to hold it with the second notch facing upwardly. In other words, the upper compound hook A can be deposited on the line C and it will hang so as to automatically present an upwardly facing notch for the cord D to be deposited therein, after which a downward

slight pull on the cord D, or even the mere weight of the plumb bob, will automatically make all fast.

For the reasons hereinbefore stated, it is 5 preferable to employ two of the N-shaped or compound hooks so that the lower one can be used for simply taking up more or less slack in the suspension cord D. This is especially preferred when the overhead 10 cord C can not be readily reached. Such cord or line is sometimes at such height above the location of the worker as to require a ladder to enable said worker to reach a hook on such overhead line. However, one compound hook alone can be used both for determining the position along the line C and the vertical position of the plumb bob, when the line C is not too high.

In order to accommodate ample length of 20 the cord D for all purposes, and yet maintain the surplus in accessible but "out of the way" position, I provide the reel or carrier E with a hook member A' having a line-gripping notch a' as illustrated by Figures 1, 4 and 5. Such reel or carrier, with ample length of cord D, and with a pair of the N-shaped hooks, and a plumb bob, may be easily carried, when not in use, in the kit or tool bag or box of a mason or 25 carpenter, or even in his pocket.

From the description already given, it will be readily understood how an electric lamp can quickly be suspended in any desired position relatively to a machine in a 30 machine shop or elsewhere. In such case, if it is not desirable to grip the circuit-wire cord in the notches of the hook A, a separate suspending cord may be employed for connecting such circuit-wire cord with the 35 said hook A.

I do not limit myself to the uses of the

invention in the manners illustrated and described, as there are various other ways of using the compound hook in connection with cords or lines employed for various purposes. For instance, such hooks may be usefully employed for taking up slack in clothes lines. The most important utility 45 however is when something carried by a cord is to be temporarily suspended from a transverse overhead line. The shape of the compound hook is such that at no time does it require any careful lateral manipulation to effect engagement with either of such cords or lines. This is chiefly due to 50 the fact that after a readily effected engagement with the overhead line, the hook automatically hangs in position to receive the cord or other line in an upwardly facing 55 gripping notch.

Having now described my invention, I claim:

A cord gripping device comprising an elongated substantially rectangular plate the outer side edges of which are straight from end to end, said plate having a notch extending from each end nearly to the other end, the walls of each notch being straight and smooth and closely approaching at the extreme inner end of the notch to enable a cord passed into either notch from its mouth to its extreme bottom to be gripped at said bottom, the two notches extending sufficiently close to opposite ends of the plate to enable the plate, when hung from a line engaged in one notch, to present the other notch in an upwardly opening direction.

In testimony whereof I have affixed my signature.

ARTHUR OUELLET.
